LOCK

Edwin W. North, Rockford, Ill., assignor to National Lock Co., Rockford, Ill., a corporation of Delaware

Application January 23, 1933, Serial No. 653,031

5 Claims. (Cl. 70—25)

This invention relates to permutation locks, and more particularly to permutation padlocks.

Objects of the invention are: to provide an improved permutation locking mechanism of the type comprising disk tumblers and a lock bolt controlled thereby; to provide an improved mechanism of said type which will automatically assume locked condition when the lock bolt is thrown to position for locking; to provide an improved mechanism of said type having means for releasably holding the mechanism in the release condition and means for automatically effecting locking action when the lock bolt is thrown to locked position; to provide in a shackle lock an improved locking mechanism which will automatically lock the shackle, the locking action of which is caused by inserting the shackle in position to be locked, and the release condition of which is effected by operation of permutation controlled means; and to provide certain detail features of improvement.

The invention will be described with reference to an illustrative embodiment thereof shown in the accompanying drawings, and will be more particularly pointed out in the claims following the description.

In the drawings:

Fig. 1 is a front elevation of the illustrative lock, which is a permutation padlock of the sliding shackle type.

Fig. 2 is a front elevation of the lock with the front housing plate and parts associated therewith removed, showing the shackle-locking mechanism in the unlocked condition and showing the shackle pulled out.

Fig. 3 is a section taken on the line 4—4 of Fig. 4.

Fig. 4 is a view similar to Fig. 3 showing the shackle inserted in position to be locked and engaged by the lock bolt but showing the disk tumblers in release position to allow the pulling out of the shackle.

Fig. 5 is a section taken at right angles to the section shown in Fig. 3.

45 The remaining figures are detail views, Fig. 6 being a holding pawl, Fig. 7 a spring washer, Fig. 8 the lock bolt, Fig. 9 a pawl which functions in the automatic locking operation, Fig. 10 a spacing washer between disk tumblers, Figs. 11, 12 and 50 13 the disk tumblers, and Fig. 14 a spacer element.

As shown in the drawings, the lock shackle 1 has a notch 2 to receive the projecting nose 3 of a swinging lock bolt 5. This lock bolt is pivoted on the fixed stud 4. The shackle 1 is represented 55 as a sliding U-shaped shackle having arms of unequal length. When the shackle is forced home in the lock housing, its short arm operates against a member 6 of the lock bolt, thereby actuating the lock bolt in a manner to swing the projection 3 into the shackle notch. In this position the lock

bolt is locked by a set of disk tumblers coacting with an index member 7 of the lock bolt. When the disk tumblers are adjusted to release the lock bolt, the pulling out of the shackle will swing the lock bolt back to the position shown in Fig. 2, this movement being effected by coaction of the bottom wall of the shackle notch with the under side of the lock bolt projection 3. In the release position shown in Fig. 2, the lock bolt is held by a pawl hereinafter described, as shown in Fig. 8, the lock bolt is constructed as a plate having flanged parts providing the functional members 3, 6 and 7, and provided with a notch 8 for engagement with the holding pawl. Said plate is formed with an elongated opening 9 to accommodate the axle of the disk tumblers, said opening being of appropriate length to allow the swinging of the lock bolt to its opposite positions.

The disk tumblers 10, 11, 12, otherwise referred to as permutation disks, are elements of a well known type of permutation mechanism including a dialing means the rotary member of which is operatively connected with one of the disks; the other disks being independently rotatably mounted and each of the disks having a shoulder or projection in the path of rotation on the adjacent disk, so that by a predetermined manipulation of the rotary dialing member, for working the "combination" for which the lock is set, the disks are brought to a position to allow the release movement of the lock bolt. Such release movement of the lock bolt is permitted by entry of the index member 7 into recesses or slots 13 of the disks, such slots having been brought into registration in a position to allow such entry by the aforesaid manipulation of the dialing means.

Dialing means is provided as shown in Figs. 1 and 3 by a rotary dial plate 15 mounted on the front of the lock housing, operable by the knob 16, and a fixed pointer 17 shown in Fig. 1 as a notch in the front face of the lock housing. The dial knob 15, which is rotatably mounted on a fixed shaft or axle 18, has a reduced extension which passes through the front wall of the lock housing and carries the first permutation disk 10, 45 which is fast on the inner end of said extension. The other two disks are loosely rotatably mounted on said shaft or axle 18, with interposed non-rotatable spacing washers 19 keyed to the axle.

The several disks are shown in detail in Figs. 11 to 13. The first disk 10 has the projection 10^a to encounter the projection 11^a of the second disk 11, which has also the projection 11^b to encounter the projection 12^a of the third disk 12, whereby the disks can pick up one another as the first disk is rotated by the dial knob. A predetermined rotation of the dial knob in one direction will set the third disk in the position shown in Figs. 2 and 4; a predetermined rotation of the dial knob in the opposite direction 60

will set the second disk in the same position, and a final predetermined rotation of the dial knob in the same direction as the first rotation will set the first disk in said position, whereupon the shackle can be pulled out with accompanying displacement of the lock bolt 5 to the unlocking or release position shown in Fig. 2.

In addition to the slots or recesses 13, the disks also have peripheral notches 14, which are brought into registration with one another when the disks are adjusted to the release position shown in Figs. 2 and 4. The purpose of the notches 14 will be presently explained. As shown in Figs. 11 to 13, the peripheries of the disk may also be provided with evenly distributed false notches to foil attempts of unauthorized persons to learn the lock combination. The disks may consist of sheet metal stampings having their lateral projections for picking up one another formed by punching out said projections as small protuberances.

As before stated, the lock bolt 5 is adapted to be held in the release position shown in Fig. 2 by means of a pawl. This pawl is indicated at 25 in Figs. 2, 4 and 6. It is pivoted on the stud 21. It is actuated to bear against the lower periphery of the plate portion of the lock bolt by the spring 22. This spring which is coiled around the stud 21 reacts between the lock housing and the projection 23 on the pawl, the tension of the spring being such that the pawl bears against the periphery of the plate portion of the lock bolt with considerable force. When the lock bolt is swung to the release position shown in 30 Fig. 2, the pawl engages the notch 8 of the lock bolt plate, thereby latching the lock bolt in said position. The periphery of the lock bolt plate is indicated in dotted lines in Figs. 2 and 4. As shown in Fig. 2, the pawl is in engagement with 35 said notch. The shape of the pawl and notch are such that a forced rotation of the lock bolt from the position shown in Fig. 2 towards the position shown in Fig. 4 will cam the pawl out of the notch. Hence the lock bolt can be swung 40 into the shackle-engaging position shown in Fig. 4 by inserting the short arm of the shackle into the lock housing and forcing the shackle home.

The mechanism includes means whereby the swinging of the lock bolt to the position shown in Fig. 4 is accompanied by an automatic deranging of the disk tumblers to effect the automatic locking of the mechanism. The means for this purpose will now be described. The lock bolt plate carries a pawl 25 which is pivotally and slidably attached thereto by means of the pivot stud 26 passing through the slot 27 in said pawl. A coiled spring 29 is connected at one end with the lock housing and at the other end with said pawl 25. This spring is contracted when the parts are in the position shown in Fig. 4, and is stretched when the lock bolt is swung to the release position shown in Fig. 2. Therefore the spring 29 tends to pull the lock bolt to the Fig. 4 position. However when the lock bolt is swung 55 to the position shown in Fig. 2 it will remain in such position because the tension of the spring 22 is sufficient to hold the pawl 20 in engagement with the notched part 8 of the lock bolt plate, or in other words a greater force than that exerted by the spring 29 will be needed to cam the pawl 20 out of the notch 8. The pawl 25 has a projection 28 which engages in the peripheral notches 14 of the disk tumblers when the parts are in the position shown in Fig. 2. Now when 60 the shackle is forced home in the lock housing, 65

it actuates the lock bolt, camming the pawl 20 out of the notch 8 and swinging the lock-bolt projection 3 into the shackle notch as previously explained. In the beginning of this movement of the lock bolt, the index member 7 is passing out of the slots 13 of the disk tumblers, which of course are prevented from rotating or freely rotating until the index member has fully passed out. Hence the pawl 25, which is held by the retractile spring 29 with its projecting lug or finger 28 entering the notches 14 of the disk tumblers, will be restrained from movement by said tumblers. That is to say, when the lug 28 abuts against the left-hand walls of the disk notches 14, the pawl will be restrained from moving with the lock bolt until the index member 7 moves out of the disk slots 13. The capacity for rotation of the lock bolt independently of the pawl 25 is allowed by the pin and slot connection at 26, 27. As soon however as the index member 20 leaves the disk slots 13, the pawl 25 will be jerked by the spring 29 to the position shown in Fig. 4. This has the effect of rotating the disk tumblers out of the release position. The rotation of the first tumbler 10 causes a corresponding rotation 25 of the dial plate from the position to which it was set for unlocking, while two other tumblers being loose are rotated or spun so as to carry their slots 13 out of registration with the slot of the first disk. It will be understood that at the 30 instant the pawl 25 is jerked by the spring 29, the lug 28 of said pawl is bearing against the left-hand walls of the disk notches 14, so that the tumblers are given a forcible rotation accompanying the movement of the pawl 25 to the position shown in Fig. 4. In this movement the lug 28 is carried clear of the tumblers, so that in the position of the parts shown in Fig. 4 there is nothing to prevent the dialing operation to adjust the tumblers for unlocking.

The operation is briefly summarized as follows: Assume the mechanism to be in a locked condition. The unlocked condition, represented in Fig. 4, is established by performing the necessary dialing operation to adjust the disk tumblers so as to bring their slots 13 to the position indicated in Fig. 4. This condition being established, the lock shackle can be pulled out, thereby swinging the lock bolt to the position shown in Fig. 2, against the resistance of the spring 29. In this operation, the index member 7 passes into the slots 13; the lug or finger 28 of the pawl 25 engages in the registering notches 14; and the pawl 25 engages the notch 8 of the lock bolt plate, the spring 22 which actuates said pawl 20 being sufficiently strong to cause the dog to hold the lock bolt in the position shown in Fig. 2. Since the index member 7 remains in the disk tumblers, their adjustment is preserved, so that it will not be necessary to perform a redialing operation to permit the reinsertion of the shackle. When the shackle is reinserted and forced home, it actuates the lock bolt, camming the holding dog 20 out of the notch 8, and swinging the lock bolt projection 3 into the shackle notch 2. In this movement, while the index member 7 is passing out of the slots 13 but before it has fully passed out, the pivot stud 26 of the pawl 25 can move in the slot 27, the movement of said pawl 25 being restrained by the engagement of its finger 28 against the left-hand walls of the disk notches 14. As soon as the index finger is clear of the disk tumblers, the spring jerks the pawl 25, causing a deranging of the disk tumblers, at the same time turning the dial. Thus the mechanism automatically locks, while by vir- 75

tue of the rotation of the dial no clue is left as to the last number of the lock combination.

If anyone after unlocking and pulling out the shackle should tamper with the mechanism by inserting a pointed tool to force the lock bolt to the locked position, the mechanism can be restored to regular condition by redialing to adjust the disk tumblers to release position and then forcing in the shackle, since the end of the short arm of the shackle bearing on the curved upper surface of the lock bolt projection 3 will exert a camming action by which the lock bolt will be swung back to the position shown in Fig. 2.

Certain constructional features of the illustrative lock will now be described.

The lock housing is shown as comprising two sheet metal parts, namely the cup-shaped rear housing member 30 and flanged front plate 31 which is fitted in said rear housing member and 20 permanently retained by spinning the housing rim over the front plate as indicated at 32 in Figs. 2 and 5. The front plate is formed to provide an annular shoulder 33 surrounding the rotary dial plate 15. Fitted in the rear housing 25 member is a flanged liner plate 34 the flange of which abuts the flange of the front plate. This liner plate 34 has the axle 18 affixed thereto, and is provided with the pivot stud 4 of the swinging lock bolt and the stud 21 of the holding dog 20. Said liner plate 34 is virtually a part of the lock 30 housing and is made as a separate part for manufacturing convenience and to stiffen and reinforce the sheet metal housing.

The element shown in Fig. 14 is keyed on the 35 axle 18. This element consists of a plate 35 arranged between the lock bolt plate and innermost disk tumbler, said plate having the arcuate spacing flanges 36 bearing against the front plate 31. A leaf spring device 37 shown in detail in Fig. 7 40 is keyed on the axle between the member 35 and innermost disk tumbler to take up clearance.

The long shank of the shackle is swiveled and 45 slidably secured in the lock housing, being provided with the reduced portion 40 which is guided in a guide provided by cooperating ears 38 and 39 struck up from the liner plate 34 and front plate 31 of the housing. The shoulder 41 on the end of the long shank of the shackle limits its outward movement.

The dial plate 15 is affixed to the dial knob 16 50 to rotate therewith. The dial knob has a portion of reduced diameter rotatably fitted in a central opening of the front housing plate 31 and the first disk tumbler 10 is fastened on the reduced inner end of the dial knob at the inner side 55 of the said front plate 31.

In Figs. 3 and 5, the numeral 42 denotes a click ring which is affixed to the dial knob and 60 yieldingly pressed by the undulating or wavy sheet metal ring 43 against the front housing plate 31, said ring being formed with a rib (not shown) which rides on an annular ribbed surface of the plate 31 so as to produce a click every time the dial knob is turned one notch.

It will be understood that the specific construction embodied in the illustrative lock is exemplary, and that changes may be made in the 65 details of construction and arrangement, so that the foregoing description is not to be taken as limiting the invention otherwise than as defined by the claims.

What I claim as my invention, and desire to 70 secure by Letters Patent, is:

1. In a permutation lock having disk tumblers and dialing means including a rotatable operating knob, a lock housing comprising a cup-shaped rear housing member and flanged front member fitted therein, a flanged liner fitted in said rear housing member, the flanges of said liner and front member abutting and the rim of the rear housing member being spun over the front member, the dialing means being arranged on the front member, an axle projecting from said liner on which said knob is rotatably mounted, one of said tumblers being attached to said knob, and the other tumblers being loosely mounted on said axle, said lock bolt being movably mounted on said liner, and a spacing element comprising a 15 plate keyed to said axle between the liner and adjacent disk tumbler, said spacing element having flanges abutting said front housing member.

2. In a permutation lock having disk tumblers and dialing means including a rotatable operating knob, a lock housing comprising a cup-shaped rear housing member and flanged front member fitted therein, a flanged liner fitted in said rear housing member, the flanges of said liner and front member abutting and the rim 20 of the rear housing member being spun over the front member, the dialing means being arranged on the front member, an axle projecting from said liner on which said knob is rotatably mounted, one of said tumblers being attached to said 25 knob, and the other tumblers being loosely mounted on said axle, said lock bolt comprising a plate pivoted to and resting against said liner, said plate having an elongated opening through which said axle extends.

3. In a permutation lock having disk tumblers and dialing means including an operating knob, a lock housing comprising rear and front members fitted together, the rim of the rear member being spun over the edge of the front member, 40 the dialing means being carried by the front member, an axle on which said knob is mounted, a tumbler attached to the knob, tumblers mounted on said axle, a lock bolt, and a spacing element keyed to the axle and having flanges abutting 45 said front housing member.

4. In a permutation lock, the combination of a housing comprising a cup-shaped rear member and a flanged front member secured together, a flanged liner in the rear housing having its flanges abutting said front member, dialing means mounted on the front member, an axle projecting from said liner, a knob rotatably mounted thereon, a tumbler attached to said knob, tumblers loosely mounted on the axle, a lock bolt mounted on the liner, and a spacing element keyed to the axle between the liner and an adjacent disk tumbler, said spacing element having projecting portions abutting said front housing member.

5. In a permutation lock including disk tumblers and a rotatable operating knob, the combination of a housing comprising a cup-shaped member and a companion member attached thereto, a flanged liner in said housing, an axle projecting from said liner upon which said knob is mounted, a lock bolt movably mounted on the liner, and a flanged spacing element fixed to said axle and abutting one member of said housing.

EDWIN W. NORTH.
